(57) **CLAIM**

The ornamental design for a combined child seat and retention flap for use with a shopping cart, as shown and described.

DESCRIPTION

FIG. 1 is a front perspective view of my new design for a combined child seat and retention flap for use with a shopping cart.

FIG. 2 is a bottom perspective view of FIG. 1.

FIG. 3 is a side elevation view of the right and left sides, which are mirror images, of FIG. 1 thereof.

FIG. 4 is a front side elevation view of FIG. 1.

FIG. 5 is a back side elevation view of FIG. 1.

FIG. 6 is a top plan view of FIG. 1.

FIG. 7 is a bottom plan view of FIG. 1.

FIG. 8 is a side elevation view of the left and right sides, which are mirror images, of the child seat in the folded position it is in when the carts are nested together; and,

FIG. 9 is a front perspective view of my new design for a combined child seat and retention flap for use with a shopping cart with the retention flap in the down position with a shopping cart shown in dotted lines which is environmental material and does not form part of the claimed design.

The broken lines in the figures are included for the purpose of illustrating elements of the combined child seat and retention flap for use with a shopping cart and form no part of the claimed design.

1 Claim, 5 Drawing Sheets
